FIG 1
N°. 1070. Surgical Coffin

W. H. Forbes.
Design for Metallic Coffin.
Patented Dec. 7. 1858.

FIG 2

FIG 3

FIG 4

Dec. 1070

William H. Forbes, of New York, N. Y.
Letters Patent No. 1070, dated Dec. 7, 1858.

The schedule referred to in these Letters Patent and making part of the same.

To all whom it may concern:

Be it known that I, William H. Forbes, of the City & County of New York, in the State of New York, have invented or produced a new and original form or configuration of a Metallic Coffin, and I do hereby declare the following to be a full and exact description of the same, reference being had to the annexed drawing, making part of this specification and in which.

Fig. 1. Is a side elevation of the Coffin closed, of which B is the upper shell or cover, which from the uniting flanges rises upward and inward in the form of an O. C. molding. D. is the lower shell or body of the Coffin formed by two parallel planes, which rise upward and outward to the uniting flange, to one of which planes the handles are secured.

Fig. 2. Is a top view of the Coffin whose outline is either elliptical or oval, reduced by the inclination inward of the O. C. molding to a suitable width and length for the glass panel E.

Fig. 3. Is a cross section view through line A. A, representing the two shells united by a box flange, the upper flange forming a rabbit and closing over the lower one and secured to it by means of screws. E. is a glass plate, placed under and fastened to the top, forming a panel.

Fig. 4. Represents a top view of a screen or cover, which is placed over the glass panel to protect it.

I claim as new and of my invention the form and configuration of metallic Coffins as represented and described.

In testimony whereof, I have this day before two subscribing witnesses,

Witnesses

Bennet Forbes

Wm. M. Raymond.

William H. Forbes.
